UNITED STATES PATENT OFFICE

HENRY G. SCHWARZ, OF DENVER, COLORADO

PRESS FOR EXTRACTING LIQUIDS

Application filed April 5, 1927. Serial No. 181,165.

This invention relates to presses for the extraction of juices from organic matter. The invention is particularly adapted for the extraction of oils and other liquids from fish and fish residue but it may also be used to advantage in the extraction of juices from pineapples, citrus fruits, grapes, apples, raisins, etc.

The principal object of the invention is to provide a press of the above stated type in which a high percentage of extraction is obtained with a correspondingly small expenditure of mechanical energy and with a negligible loss of solids.

Other novel features reside in details of construction and the combinations and arrangements of the elements and parts which cooperate to attain the before-mentioned object as will be fully set forth in the course of the following description.

In the accompanying drawings in the several views of which like parts have been similarly designated,

Figures 1A and 1B represent conjointly a sectional elevation of a press constructed in accordance with the present invention,

Figure 2, a vertical section along the line 2—2, Figure 1A,

Figure 3, a similar section taken on the line 3—3, Figure 1B,

Figure 4, a section along the line 4—4, Figure 1A,

Figure 5, an enlarged sectional view of the adjustable member of the press which controls the discharge of the solid residue of the extraction process; and

Figure 6, an enlarged section on the line 6—6, Figure 2.

The press as shown in the drawings, comprises a base or foundation structure 5 including bearings 6 and 7 for the support of the rotary element of the machine. The rotary element includes a horizontal shaft 8, a hollow conical body 9, rigidly mounted thereon, and a helical blade or screw 10 extending around the periphery of the body.

A suitable reduction gearing 12 connects the shaft with a conveniently located motor and a clutch 13 serves to control the operative connection of the gearing with the mo-

tor in the usual manner. The bearing 7 at the end of the body opposite to that at which it connects with the motor, is constructed to resist end-thrust.

A cylindrical screen 14 horizontally supported on the base, surrounds the rotary body in coaxial relation thereto to provide an annular space 15 of gradually decreasing width through which the material fed into the screen through an opening 16 at an end thereof, is forcibly impelled by the action of the helical blade whose peripheral edge extends in close adjacency to the inner surface of the screen.

A stuffing box 17 at the feed end of the screen prevents leakage of liquids around the shaft. The screen is supported on the base by a head 18 which has the feed opening and the stuffing box mentioned hereinbefore, and a head 19 which provides an annular passage 70 for the final extraction of the juices from the material and the discharge of the solid residue as will hereinafter be more fully explained.

The screen 14 is fastened to the heads by machine bolts 20 together with a casing 21 which surrounds the upper portion of the screen. Rods 22 extending through slotted lugs 23 and 24 on the heads exteriorly of the screen and secured by nuts or other means, fasten the heads together, and the screen between the heads is reenforced by surrounding bands 25.

Rods 26 fastened to certain of the bands extend transversely through the space 15 between the rotary body and the screen to prevent the material forced through the space by the screw blade from rotating with the body.

The conical body is as stated before, smallest at the feed end of the screen and the pitch of the helical blade decreases progressively toward the larger end of the body to restrict the advance of the material through the compression space in ratio to the uniform increase in pressure owing to the gradually decreasing width of the space.

The hollow conical body has at its larger end a plurality of screen-covered openings 27 for the passage of juices to its interior at 100

the point of highest pressure and it has within in the head 19 at the discharge end of the machine, a hollow cylindrical open-ended extension 28 provided with screen covered openings 29 through which issue part of the juices extracted from material pressed through an annular passage 30 between the extension and the head, which passage is continuous with the compression chamber 15.

10 The head 19 is composed of two flanged sections supported one upon the other and fastened together by bolts 31 so that the upper section may be lifted for cleaning purposes after the rods 22 by which the two screen heads are connected have been removed through the slots of the lugs in which they are fastened. The two sections of the head are flanged at opposite ends and ribbed between their flanges, for the support of screens 20 32 which are opposed in spaced relation, to the screened surface of the part 28 of the rotary element, and the lower section has openings 33 through which the juices passing through the screens are discharged.

25 Fastened between the flanges of the head sections are baffles 34 which project into the annular space 30 around the rotary element within the head to prevent the material passing through the space from turning with the element. These baffles are sharp edged at their ends forward with relation to the movement of the material so that they may cut into the material and thereby facilitate the onward movement thereof through the passage 30.

30 Fastened at the end of the rotary element exteriorly of the stationary head is a flanged, annular hard metal ring 35 inside a shield 36 which prevents the discharge of matter beyond the end of the machine. The shield has at its lower end a trough-shaped pocket 37 to receive matter that passes through the space between the flange of the ring and the inner edge of the shield.

40 45 The ring is externally screw-threaded for the application of a nut 38 which is in driving connection with a member 39 adapted to control the discharge of the solid residue from the passage 30 between the rotary element and the head.

50 The controlling member consists of a ring slidably fitted around the cylindrical extension of the rotary element and having a beveled end portion adapted to enter the passage between the extension and the head of the screen. By turning the nut on the screw-threads of the ring, the member 39 may be advanced into the passage thereby varying the width of the outlet thereof and controlling the discharge of solids through said outlet. Both the nut and the controlling member are made in flanged sections connected by bolts and the flanges 40 on the nut provide a convenient means for its rotation.

60 65 The member 39 is held against rotation on

the rotating element by keys 41, and it is connected with the nut by a swivel joint. A circumferential flange 42 on the nut, extending across the joint between the flange 43 on the ring 35 and the inner edge of the shield aids in preventing solids from passing through said joint into the trough 37.

70 75 In the operation of the machine, the material is fed through the opening 16 into the compression space 15 and is impelled through said space by the action of the screw blade on the rotary element. The gradually narrowing width of the space between the cylindrical screen and the conical body of the rotary element causes the material to be subjected to correspondingly increased pressure and owing to the progressively decreasing pitch of the screw blade, the advance of the material is correspondingly retarded.

80 85 The oils and other juices extracted from the material pass through the surrounding screen and at the point of greatest pressure at the largest end of the cone, an additional outlet for the liquids is provided by the screen-covered openings in the conical body. The residue of the material after it is disengaged by the screw is pushed into the annular passage 30 between the cylindrical end portions of the rotary element and the inner surface of the head, in which passage the remaining juices are expressed from the material to pass through the screen covered openings at opposite sides of the passage.

90 95 The residue finally passes through the outlet of the passage, the area of which is regulated by adjustment of the beveled member 39 as hereinbefore explained.

100 105 The rods 26 and the baffles 34 keep the material from turning in the compression spaces. It is an important feature of the invention that the screens at the points of greatest pressure, which cover the openings in the conical body 9 and the openings at opposite sides of the annular passage 30 are of smaller mesh than the screen around the body portion of the rotary element thereby preventing the discharge of solids with the juices in the zone of greatest pressure.

110 115 It will be apparent that the pressure exerted upon the material is gradually increased at a uniform ratio and that in consequence the machine is free from stresses produced in other presses by stepped changes in pressure, and will by a continuous discharge subject to a continuous feed, operate at all times at a 120 maximum capacity.

Having thus described my invention, what I claim and desire to secure by Letters Patent is:

125 1. A press of the character described comprising a cylindrical screen element having a discharge opening, a rotary element including a conical body in the screen element, a flanged cylindrical extension without the same, and a helical screw blade on the conical 130

body, a head spaced from the extension to provide a passage for the discharge of solids, and an annular shield beyond the passage, the flange on the extension being inside the opening of the shield.

- 5 2. A press of the character described comprising a cylindrical screen element having a discharge opening, a rotary element including a conical body in the screen element, a flanged cylindrical extension without the same, and a helical screw blade on the conical body, a head spaced from the extension to provide a passage for the discharge of solids, and an annular shield beyond the passage, the flange on the extension being inside the opening of the shield, and the shield having a pocket at its lower end.

- 10 3. A press of the character described comprising a cylindrical screen element having a discharge opening, a rotary element including a conical body in the screen element, a flanged cylindrical extension without the same, having a screw-threaded end portion, and a helical screw blade on the conical body, 15 a head spaced from the extension to provide a passage for the discharge of solids, a beveled member movable on the extension to vary the outlet of the passage, and a nut cooperative with the screw thread of the extension 20 and in driving relation to the member.

- 25 4. A press of the character described comprising a cylindrical screen element having a discharge opening, a rotary element including a conical body in the screen element, a flanged cylindrical extension without the same, having a screw threaded end portion, and a helical screw blade on the conical body, 30 a head spaced from the extension to provide a passage for the discharge of solids, a beveled member movable on the extension to vary the outlet of the passage, a nut cooperative with the screw thread of the extension and in 35 driving relation to the member, and an annular shield beyond the passage, the flange on the extension being in the opening of the shield, and the nut having a flange covering the joint between the shield and the flange 40 on the extension.

45 In testimony whereof I have affixed my
50 signature.

HENRY G. SCHWARZ.
